UNITED STATES PATENT OFFICE.

ALFRED H. BUCKLEY, OF PHILADELPHIA, PENNSYLVANIA, ASSIGNOR TO AMERICAN CAN COMPANY, OF NEW YORK, N. Y., A CORPORATION OF NEW JERSEY.

INCASED SHIPPING-CAN FOR OIL AND OTHER FLUIDS.

1,063,503.

Specification of Letters Patent.

Patented June 3, 1913.

Application filed February 14, 1910. Serial No. 543,650.

To all whom it may concern:

Be it known that I, ALFRED H. BUCKLEY, a citizen of the United States, residing in Oak Lane, Philadelphia, in the county of Philadelphia and State of Pennsylvania, have invented a new and useful Improvement in Incased Shipping-Cans for Oil and other Fluids, of which the following is a specification.

10 My invention relates to incased shipping cans for oil and other fluids.

The object of my invention is to provide an improved construction of incased shipping can suitable for shipment of oils and other fluids having a low flash test, which will be composed of few parts, be capable of being cheaply manufactured, and in which the pouring nozzle, as well as the can itself, will be entirely and completely inclosed and protected, in which the can will be firmly, securely and immovably held in position in the case when the lid of the case is closed, in which the can may be freely removable from the case when the lid is open, and from which the oil or other fluid may be conveniently poured.

My invention consists in the novel construction of parts and devices and in the novel combinations of parts and devices herein shown and described, and by which this object or result is practically accomplished, the same being more particularly set forth in the claims.

In the accompanying drawing forming a part of this specification, Figure 1 is a perspective view of an oil can and case embodying my invention, showing the lid partially open. Figs. 2 and 3 are vertical cross sections on lines 2-2 and 3-3 respectively, showing the lid closed.

In the drawing, 1 represents an oil or other fluid shipping can, having a tapering top or breast 2 and pouring nozzle 3, and provided with bail ears 4, wire bail 5 and handle 6, the can being preferably of a rectangular shape in horizontal cross section.

7 is the case of box-like or rectangular shape, of a size adapted to receive the rectangular can 1. The case 7 has a shortened front 8, extending preferably to about the height of the lower edge of the tapering top 2 of the can. The sides 9 and back 10 of the case project slightly above the upper end of the can nozzle 3. The shortened front 8 of the case affords a seat 11 for the deep

curtain 12 at the front of the hinged lid 13 of the case. The hinged lid 13 is provided with a pair of deep can holding cleats 14, which fit inside the upright sides of the case and engage, when the lid is closed, at their lower edges 15 the tapering top 2 of the can, so that these cleats on the lid will themselves serve as a device for holding the can firmly, snugly and immovably in position in the case. The lid 13 is nailed to these cleats 15, as is also the curtain 12 of the lid, thus giving the lid a firm and strong construction. The lid is hinged at its back edge to the back 10 of the case by hinges 16.

The lid is held firmly in its closed position on the case preferably by means of a hinged hasp 17 secured by a strap 18 to the curtain 12 of the lid 13, coöoperating with a bent pivotal fastener 19, which is pivotally secured to the front 8 of the case by a strap or plate 20.

When the lid is closed and locked in its closed position by the hasp and fastener, the deep depending cleats on the lid by their engagement with the tapering breast of the can firmly hold and lock the can firmly in the case. When the lid is open, its hinges permit it to swing back flat against the upright back of the case, and the can 1 is entirely free to be lifted out of the case by its handle and tilted down over the upper edge 21 of the shortened front 8 of the case as a fulcrum for conveniently pouring the liquid from the can. The upright sides 9 of the case serve as guides for the can when the can is being tilted over the upper edge of the case front as a fulcrum in pouring, as will be readily understood from the dotted lines in Fig. 3 of the drawing.

I claim:

1. An article of manufacture of the character described comprising, in combination: a sheet metal can having a tapered top and a pouring nozzle; and a case provided with a hinged lid and entirely inclosing the can and its nozzle, said lid being free from engagement with the nozzle when closed and having a rigid member fixedly secured thereto which is adapted to engage the tapered top of the can at a point near the junction of said top with the body portion to thereby hold the can firmly in position when the lid is closed and prevent the nozzle from coming in contact with the lid when the can is inverted, substantially as specified.

2. An article of the character described comprising, in combination: a sheet metal can having a tapered top and pouring nozzle; and a case having a hinged lid and entirely inclosing the can and its nozzle, the lid being free from engagement with the nozzle when in closed position, said lid being provided with a pair of parallel depending cleats fitting inside the case on opposite sides of the can nozzle and engaging the tapered top of the can at points adjacent the junction of the top with the body portion to thereby hold the can firmly in position without danger of movement when the lid is closed and preventing the nozzle from coming in contact with the lid when the can is inverted, the can being freely removable from the case when the lid is in open position, substantially as specified.
3. An article of the character described

comprising, in combination: a sheet metal can having a top and pouring nozzle; and a case having a hinged lid and entirely inclosing the can and its nozzle, said lid being free from engagement with the nozzle when in closed position and having secured thereto rigid depending cleats fitting inside the case and engaging the top of the can on opposite sides of the nozzle to hold the can firmly in position within the case when the lid is closed to thereby prevent the nozzle from coming in contact with the lid when the can is inverted, said cleats being movable with the lid to thereby permit the can to be readily removed from the case when the lid is in opened position, substantially as specified.

ALFRED H. BUCKLEY.
